UNITED STATES PATENT OFFICE

117,096

DESIGN FOR AN ILLUMINATED WRITING PAD

Carleton R. Good and Wendell T. Hegg,
River Forest, Ill.

Application July 20, 1939, Serial No. 86,119

Term of patent 7 years

To all whom it may concern:

Be it known that we, Carleton R. Good and Wendell T. Hegg, citizens of the United States and residents of River Forest, in the county of Cook and State of Illinois, have invented a new, original, and ornamental Design for an Illuminated Writing Pad, of which the following is a specification, reference being had to the accompanying drawing, forming part thereof.

Fig. 1 is a perspective view of an illuminated writing pad embodying our design; and

Fig. 2 is a view in side elevation of the writing pad.

We claim:

The ornamental design for an illuminated writing pad, as shown.

CARLETON R. GOOD.
WENDELL T. HEGG.
